CHARGE FORMING DEVICE

Frank C. Mock, South Bend, Ind., assignor to
Bendix Products Corporation, South Bend, Ind.,
a corporation of Indiana

Application August 3, 1940, Serial No. 350,519

20 Claims. (Cl. 261—69)

This invention relates to charge forming devices of the pressure feed or closed fuel system types and is particularly concerned with the design and/or arrangement of the parts to facilitate assembly and reduce the cost of manufacture. The invention is also concerned with the provision of means for automatically eliminating air, fuel vapors, and water from the various chambers of the device and of means for cutting off all fuel flow to the engine when it is to be stopped. The present application is a continuation-in-part of my copending application Serial No. 202,206, filed April 15, 1938.

Charge forming devices of the pressure feed type have certain inherent advantages, as compared to a conventional carburetor, which make them particularly adaptable for use in aircraft, and as a consequence have been largely developed for use in the aircraft engine field. In the past the cost of devices of this type has been relatively high, partially because a relatively small number of each of a multiplicity of models are manufactured. This condition results from several interrelated factors. The total aircraft engine production, which in its entirety is relatively small, consists of a moderately large number of engine models of various sizes or designs. As will be apparent to one skilled in the art, each model or size of engine requires a more or less modified carburetor, thus the air passages and venturis may be of various sizes or shapes, the fuel control systems may be of various types, or the fuel discharge nozzles may have to be of different forms or differently arranged to produce the desired fuel distribution pattern necessary for satisfactory engine operation.

Furthermore, each model engine may be used in several types of aircraft, for example, a given model might be used in commercial transports, military bombers and pursuit planes, each of which is subjected to an entirely different type of service having different fuel control requirements and requiring a modified carburetor. Also, a particular model engine may be used on aircraft of a given type, such as pursuit planes, but having fuselages built by different manufacturers which require modified carburetor controls or, because of space limitations, variations in the size, shape, or arrangement of the induction passage or other parts of the carburetor. Thus a different carburetor model may be required not only for each engine model but also for each type of service or make of fuselage in which the engine model is to be used.

The problem of eliminating air, fuel vapor, and

water is present in all the models and provision must therefore be made to eliminate these undesirable fluids if and when they appear. It is furthermore desirable to provide in all models a means for cutting off all fuel flow to the engine when it is to be stopped to eliminate the tendency for the engine to continue to run, because of pre-ignition in the engine cylinders, after the ignition is turned off.

From the above factors, it will be readily apparent that a multitude of aircraft carburetor models must be manufactured, each differing from the others in certain respects but having some parts in common with at least a portion of the others. By designing the carburetor so as to consist of several separate units each capable of separate assembly and then assembly with the other units to make up a complete charge forming device, all units that are common to one or more models may be manufactured and assembled on one production line, thus decreasing the cost of production. Furthermore, each unit, particularly those having some function which enters into the fuel metering ability of the device, may be individually tested and calibrated before final assembly. Variations resulting from manufacturing tolerances which would be difficult to isolate in the complete device may thus be traced to the individual unit before final assembly with other units in making up the complete device.

It is therefore an object of the present invention to provide a charge forming device comprising several separate sub-assemblies.

A further object is to provide a charge forming device in which the parts most likely to be varied for adaptation to various engines or installations are included in separate sub-assemblies of the complete device.

A further object is to provide a charge forming device comprising several separate sub-assemblies which may be individually tested and calibrated.

A further object is to provide means whereby the charge forming device will automatically eliminate air, fuel vapor, and water from the chambers of the device.

A further object is to provide an improved means for cutting off all fuel flow to the engine when it is to be stopped.

A still further object of the invention is to provide a charge forming device which may be manufactured in a multiplicity of models at reasonable cost.

A still further object is to provide an improved

charge forming device of the pressure feed type. Other objects and advantages will be apparent to one skilled in the art from the following detailed description taken in connection with the appended drawings, in which:

Figure 1 is a top view of a charge forming device embodying the invention, the regulator unit thereof being shown in section;

Figure 2 is an elevational view in section, taken on the line 2—2 of Figure 1, showing the throttle body, the automatic mixture control unit, the fuel regulator unit and the adapter section;

Figure 3 is a side elevation of the device of Figure 1 with the fuel control unit sectioned on line 3—3 of Figure 1 and with portions of the regulator unit broken away;

Figures 4, 5, 6 and 7 are elevational views of the mixture control valve in its idle cut-off, automatic-lean, automatic-rich and full-rich emergency positions respectively; and

Figure 8 is a diagrammatic view of the entire charge forming device in which the separable units and their interconnecting passageways are shown in a single plane, the units being maintained substantially at their respective levels.

With particular reference to Figures 1, 2, 3 and 8 there is shown a charge forming device of the pressure feed type having five separate units or sections, a body A, an automatic mixture control unit B, a fuel regulator unit C, a fuel control unit D and a fuel nozzle adapter section E. Each of said units or sections is capable of separate assembly and testing and subsequent attachment to the other units or sections to make up a complete device.

The body A comprises an induction passage having two barrels, each of which has an inlet 10 and an outlet 11 controlled by a throttle 12 secured to a rotatable shaft 13. A flange 15 at the top of the body A is adapted to have secured thereto a scoop or air entrance section (not shown) which is generally of the elbow type. A large venturi 17 is secured in each of the induction passage barrels and is formed with an annular chamber 18 communicating with the air inlet 10 through tubes 19 which project into the induction passage so as not to transmit to said chamber water or rain which is carried into the scoop and runs down the walls of the induction passage. Air passages 21, 22, 23 and 24 communicate the chamber 18 with the bottom of a chamber in the regulator unit C, yet to be described. A by-pass 25 connects passages 21 and 24, and has a valve 26 which is closed at all times except when operating in the "emergency-rich" setting as will be explained hereinafter. Small venturis 29 extend into the venturis 17 and have three prong-like members 30, 31 and 32 secured to the top portion of the body A by screws 33. An annulus 35 opening into the throat of venturi 29 communicates by means of an air passage 36 in the prong-like member 32 with an air passage 37 leading downwardly in the body A. The passage 37 communicates adjacent the bottom thereof with the induction passage posterior to the throttle by means of a restricted bleed 38 and with the lower portion of a chamber of the regulator C, yet to be described, by means of an air passage 39.

The automatic mixture control unit B comprises a base member 42 into which is threaded a cap 43. A sealed chamber having an upper non-deformable portion 44 and a lower deformable bellows portion 45 is threaded into the top of the cap 43 and secured thereto by lock-nut

46. A valve element 47 is connected to the lower movable wall of the bellows to be actuated thereby and is slidably received in a central aperture in the base member 42 for controlling a port 48 forming a communication between air passages 22 and 23. A gasoline-resistant rubber-like seal 49 is provided in a groove on the lower end of base 42 for sealing the base in the passage 22. The internal structure and arrangement of parts of the unit B are more particularly described in my copending application Serial No. 120,654, filed January 15, 1937. Ports 50 and 51 are respectively provided in the base 42 and cap 43 to permit entering air to circulate through the cap 43. The automatic mixture control unit is first assembled and may be separately tested by subjecting it to various external pressures and checking the needle travel or the rate at which it restricts a master passage in a test fixture. The calibrated unit is then threaded into the body A. The unit B is so designed, as described in the above copending application, that the valve 47 variably restricts port 48 in response to variations in entering air pressure and temperature.

The regulator unit C comprises three main castings or sections 54, 55 and 56, the section 56 being provided with two or more studs 57 (Figure 1) which extend through sections 54 and 55 for purpose of separate assembly of the regulator unit. The section 54 has a housing 58 integrally cast therewith which includes a fuel inlet 59 (Figure 3) adapted to receive fuel from a source of fuel under pressure such as a by-pass type constant pressure fuel pump. A cylindrical filter of fine mesh screen 60 within the housing 58 is urged against an annular seat 61 by a spring 62 cooperating with a cap 63. A central bolt 64 secures the cap 63 to the housing, a gasket being provided for purpose of sealing. A vapor outlet 65, adapted to be connected to the fuel tank, is provided in the uppermost portion of housing 58. A float valve indicated generally at 66 controls the vapor outlet. A passage 69 communicates the interior of the cylindrical screen 60 with an annular chamber 70 in a sleeve-like extension 71 of the regulator section 54. A shouldered sleeve 72 having a tapered valve seat 73 is secured in the extension 71 by locking nut 74 and packing 75 and is provided with radial apertures 76 closely adjacent the seat 73 which communicate with the annular chamber 70. A tapered valve 79 is slidably received in the sleeve 72 and is carried by a plug 80 threaded on a valve stem 81. A diaphragm 82 serves to seal the outer end of the valve member to prevent leakage of fuel therewith from the annular chamber 70. The diaphragm preferably has an effective area equal to the area of the tapered valve opening to balance the pressure differential across the valve as will appear more fully hereinafter. A cap 83 seals the end of the extension 71.

The regulator section 55 is an annular member having an apertured internal web 84. The section 56 has a plurality of spoke-like members 85 carrying a central apertured hub 86 which is closed at one side by a cap 87.

A regulator control rod 90 is connected to the valve stem 81 by a double universal joint 91. Diaphragms 92, 93, 94 and 95 are secured at their central portions to the control rod 90, being maintained in spaced relation by clamping hubs 96. The diaphragms 92 and 94 are respectively secured at their outer edges to the hub 86 and

web 84; and diaphragms 93 and 95 are secured at their outer edges between the main sections of the control unit. An annular disc 97 is secured between the sections 54 and 55 and has a finger-like projection 98 to which is riveted a flat spring 99 bearing against the control rod 90 and urging the valve 79 to the right in a direction to open the valve. A screw 102 is provided in the end of the section 54 and engages the spring 99 for purpose of adjusting the spring force urging the valve open. Guide members 103 are secured to the hub 86 and web 84 and engage the clamping hubs 96 to support and guide the control rod assembly.

The regulator unit C is thus capable of separate assembly, the various sections being held in assembled relation by the assembly bolts 57. The assembled regulator may be tightly clamped in a fixture which holds the three sections 54, 55 and 56 securely together and the various chambers checked for leaks. A flange 110 is provided on the throttle body A and a matching flange 111 on the section 56 of the regulator. A plurality of studs 112 are mounted in the body A and are adapted to receive the assembled regulator C. Nuts 113 on the studs 112 hold the regulator unit to the throttle body and also clamp the sections of the regulator tightly together, gaskets being provided at the various surfaces to prevent fuel leakage.

The regulator is thus comprised of six chambers 116, 117, 118, 119, 120 and 121. Chamber 117, preferably referred to as the unmetered fuel chamber, is connected to chamber 116 by means of a fuel pressure transmitting passage 123 and to chamber 121 by means of a fuel pressure transmitting passage 124 drilled in the regulator sections and one of the spoke-like members 85. Unmetered fuel chamber 117 communicates with the control unit D by means of a fuel conduit 127 which leads from the chamber adjacent the bottom, as indicated at 128 in Figures 1 and 8, through a lower flange 129 (Figure 3) at which the regulator and control units are connected. A vent passage 130 passing through a similar upper flange 131 interconnects the unmetered fuel chamber 117, adjacent the top as indicated at 132, and the control unit. The chamber 118, preferably referred to as the metered fuel chamber, is connected to the control unit D by means of a fuel passage 134 leading from the bottom of chamber 118, as indicated at 135 of Figure 2, and passing through the lower flange 129, and also by means of a fuel passage 136 leading from adjacent the top of chamber 118, as indicated at 137, and passing through the upper flange 131.

Chamber 119 is connected to the air passage 37 in the throttle body by means of air passages 39 and 140 which respectively enter the chamber 119 adjacent the bottom and top thereof and transmit venturi suction thereto. Chamber 119 is also connected to chamber 120 by means of a restricted bleed passage 141 located in the bottom portion of the regulator. The previously described air passage 24 leads to the chamber 120 of the regulator unit and transmits air scoop pressure thereto.

The fuel control unit D which is first assembled and then bolted to the regulator at flanges 129 and 131 is additionally supported by means of a bracket 150 bolted to both the fuel control unit D and the body unit A. The fuel control unit may best be understood from Figures 3 and 8. Fuel is received by the control unit from the regulator unit through the fuel conduit 127 and

is delivered to the discharge nozzle adapter section through a fuel outlet conduit 151 and a pipe 152 connected to the control unit at the upper left corner as shown in Figure 3 or at the upper right corner as shown in the diagrammatic Figure 8. The fuel conduit 127 is variably controlled by an idle needle 153 which is moved to the right to restrict the conduit as the throttle 12 approaches closed position. The needle 153, as shown, is a cylindrical member counterbored at one end and having a narrow vertical slot and is adapted to be moved by a lever 154 received in the slot and secured to a rotatable shaft 155 having an operating lever 156 (Figure 1) which is connected by link 157 to a throttle operating lever 158 secured to the throttle shaft 13. An adjustment screw 159 is provided between the lever 156 and link 157 for adjusting the idle needle position relative to the throttle. A spring 158, the one end of which is received within the counterbored end of the idle needle 153, urges the needle to the right (Fig. 3) to eliminate any play between the needle and lever 154.

The conduit 127 leads into a relatively large fuel chamber 160 in the fuel control unit D. An "automatic-lean" metering jet 161 connects the chamber 160 with a chamber 162 having a fuel conduit 163 leading to a chamber 164, the fuel conduit 163 being controlled by a mixture control valve 165 of the disc type which is urged to the right by a spring, not shown. A bleed passage 166 is also provided leading from the top of the chamber 162 to the chamber 164 and is controlled by valve 165. The valve 165 is connected to a rotatable shaft 168 having an operating lever 169 attached thereto and is shown in Figure 3 in its "idle cut-off" position, a position which is used when the engine is to be stopped. A cup-like member 167 is also secured to the shaft 168 to be rotatable therewith and is provided with an arm 171 connected through a linkage (shown diagrammatically in Figure 8 as a cable) to the valve 26 in the air passage 25. A spring loaded valve assembly, indicated generally at 172 is received in the bottom of chamber 162 and controls the communication between passage 134 and chamber 162. The valve 172 is operated by a cam 173 on the end of the mixture control shaft 168 and is open at all times except when shaft 168 is in the "idle cut-off" position.

A power enrichment metering jet 175 communicates the chamber 160 with a small chamber 176. A fuel conduit 177 including an "automatic rich" metering jet 178 leads from the chamber 176 to the chamber 164 and is controlled by the mixture control valve 165. A fuel conduit 180 leads from the chamber 176 to an economizer chamber 181 which is connected to the chamber 162 by a fuel conduit 182, the chamber 162 communicating with the chamber 164 through port 163 controlled by the valve 165. An economizer valve 183 is spring loaded against a seat 184 and controls the communication between fuel conduit 180 and chamber 181. The valve 183 has a diaphragm 186 secured thereto which forms a chamber 187 with an economizer cover plate 188. A small bleed passage 189 connects the top of chamber 187 to the passage 130 which leads from the unmetered fuel chamber 117 to the chamber 164 and is controlled by the valve 165. A passage 191 leads from the bottom of chamber 187 to the fuel conduit 127 from the unmetered fuel chamber 117.

The mixture control valve 165 is of a contour best shown in Figures 4 to 7 and is operated by

the pilot through a link, not shown, connected to the operating lever 169. The valve has four control positions as indicated in Figures 4 to 7. In the idle cut-off position of Figure 4 the bleed passages 130 and 166 as well as the fuel feeding conduits 163 and 177 are all closed. The valve when in this position cuts off all communication between the unmetered and metered fuel chambers 117 and 118. In the automatic lean position of Figure 5 the valve 165 only cuts off the conduit 177. In the automatic-rich position of Figure 6, passages 130 and 166 and fuel conduits 163 and 177 are open. In changing from the automatic-rich position to the full rich emergency position of Figure 7, no change takes place relative to the passages 130 and 166 and conduits 163 and 177. However, as the lever 169 moves through this increment of travel, the linkage (Figure 8) connecting lever 169 and valve 26 opens the valve 26 in the air by-pass passage 25 around the automatic mixture control unit. The full-rich emergency position, as its name indicates, is used only in an emergency when the pilot desires to eliminate the automatic altitude control accomplished by the bellows controlled valve 47.

After assembly, the fuel control unit D may be separately tested in a test fixture which supplies fuel to conduit 127 at a constant pressure or gravity head. The rate of fuel flow through the unit with the lever 169 in each of its several positions will indicate whether there are any leaks in the casting or whether a metering jet of incorrect size has been used.

The adapter section E (Figure 2) has a flanged inlet 201 of a shape adapted to be secured to the outlet flange 202 of the body A and has an outlet flange 203 of a shape adapted to be secured to the intake manifold of the engine. The adapter may be of the straight through type, the elbow type, the angled type as shown, or of any shape desired. Thus various adapter sections may be used to fit a given carburetor to engines having various types of intake manifolds. A pressure responsive fuel discharge nozzle indicated generally at 204 is mounted in the side of the adapter E and receives fuel from the control unit D through pipe 152 and a conduit 206 formed in the wall of the adapter E. The fuel discharge nozzle may be of any of the types or arrangements disclosed in the copending application of Mock and Partington, Serial No. 243,067, filed November 30, 1938, or in my copending application, Serial No. 350,517, filed August 3, 1940. An acceleration pump indicated generally at 210 is positioned in the adapter section E and may be of any of the types disclosed in the copending application of Mock and Moore Serial No. 272,990, filed May 11, 1939. The acceleration pump may be assembled as a unit and inserted into the adapter.

Assuming the carburetor has been installed on an engine and does not contain any fuel, the procedure for filling the carburetor, starting the engine, and operating the engine, would be as follows. The procedure for filling the carburetor may best be understood from Figure 8. The mixture control valve is placed in the automatic-rich position, thus uncovering the passages 130, 166, and conduits 163 and 177 and opening the valve 172. Fuel is then supplied to the fuel inlet 59 under positive pressure by means such as a hand-operated wobble pump in the fuel line leading from the fuel tank to the inlet 59. The idle spring 99 normally holds the valve 79 off of its seat and therefore allows the fuel supplied to enter chamber 117 and flow through conduit 127 into the

chamber 160. The fuel rises uniformly in chambers 117 and 160 until it reaches the jet 161. At this time there is fuel in chamber 117 to the level of the jet 161 but none in chamber 118. The fuel in chamber 117 urges the diaphragm 93 and attached rod 90 to the left tending to close the valve 79 against the force of spring 99. The level determined by the jet 161 must be insufficient to close valve 79, otherwise the inflow of fuel would be cut off. Additional fuel entering chamber 117 flows through metering jet 161, past valve 172, through passage 134 and into chamber 118. The fuel level in chamber 117 thus remains substantially constant until fuel in chamber 118 reaches the same level. The fuel level then rises uniformly in the chambers 117 and 118 of the regulator and in the fuel control body. Air which would otherwise be trapped in the top of the chambers 117 and 118 of the regulator and of chambers 162 and 167 of the fuel control unit is vented through passages 130, 136, 166 and 169 respectively. As the fuel rises in the units C and D the air is forced out through the pipe 152, from the highest point of the control unit D, to the discharge nozzle. After the device has been filled a small additional quantity of fuel is supplied thereto, causing fuel to deliver from the nozzle 204 for priming the engine to assist in starting.

During operation, the pilot controls the air supplied to the engine and the fuel is controlled automatically as hereinafter described. Air flow through the induction passage creates a differential in pressure between the throat of venturi 29 and the air inlet which is proportional to the square root of the quantity of air flowing. The venturi suction is transmitted to the chamber 119 of the regulator through passages 36, 37, 39 and 140. The air inlet pressure is transmitted to the adjacent regulator chamber 120 through tubes 19 and passages 21, 22, 23 and 24. Venturi suction and air scoop pressure acting on opposite sides of diaphragm 93 create a net force to the right, tending to open the fuel inlet valve 79, which is proportional to the square root of the quantity of air flowing. The sealing diaphragms 94 and 92 are respectively acted on by these two air pressures and merely have the effect of decreasing the effective area of the diaphragm 93 without disturbing the proportional relationship between the air flow and the force on the control rod 90.

Fuel is continuously supplied to the annular chamber 70 under positive pressure by means of an engine driven pump, not shown, or from any source of fuel under pressure. The fuel then flows into chamber 117, through conduit 127 and into chamber 160. If the mixture control valve 165 is in the automatic-lean position of Figure 5 and the engine is operating at a moderate power output, fuel will flow through the automatic-lean metering jet 161, into chamber 162, through port 163, into chamber 164, through conduit 151, pipe 152 and conduit 206 to the discharge nozzle 204. Fuel in the nozzle 204 urges the diaphragm of the nozzle to the right to open the nozzle valve and allow fuel to discharge into the air flowing through the induction passage. The fuel pressure in chamber 164 will be less than that in chamber 160 by an amount proportional to the square root of the quantity of fuel flowing through orifice 161. The unmetered fuel pressure in chamber 160 is equal to that in the unmetered fuel chamber 117 of the regulator because of the free communication therebetween through conduit 127; and the metered fuel pressure in cham-

ber 164 is transmitted undiminished to the metered fuel chamber 118 through passage 136. Thus the differential pressure across metering jet 161 creating fuel flow is also present across the diaphragm 95 and creates a force tending to close valve 79 which is proportional to the square root of the quantity of fuel flowing. The unbalanced force normally created by the differential pressure across the poppet valve 79 is balanced out by subjecting the diaphragm 82 connected to the valve to an equal but opposite differential pressure. The control rod 90 will therefore position itself such that the air force and fuel force are maintained equal, thus maintaining a constant proportion between the quantities of air and fuel flowing.

At idle, the idle spring engages the control rod 90 and creates a force, in addition to the air force, tending to open the valve 79 and increase the fuel flow. The idle spring force is of appreciable amount relative to the air force at idle and consequently provides a substantial idle enrichment. As the air flow and consequently the air force increase, the idle spring force becomes of lesser relative amount thereby decreasing the idle spring enrichment. As the air flow further increases the rod 90 may move completely off of the spring 99 thus eliminating its effect. It has been found desirable to adjust the idle spring to produce an excessive enrichment at idle and then decrease the enrichment by the throttle controlled idle needle 153 which is adjusted to restrict the conduit 127 at closed throttle and is withdrawn from its restricting position as the throttle moves from its idle position. Any desired enrichment at idle or near idle position may be obtained by the contour and adjustment of the tip of valve 153.

As the air flow and consequently the power output increase, the venturi-to-scoop air pressure differential and the unmetered-to-metered fuel pressure differential will increase. Unmetered fuel pressure is transmitted to chamber 187 by the passage 191 from the passage 127 and acts to the left on the economizer diaphragm 186. Metered fuel pressure is transmitted to the chamber 181 through the conduit 182 from the chamber 162 and acts to the right on diaphragm 186. When the differential pressure across the diaphragm 186 reaches a predetermined value the economizer valve 183 opens and allows fuel to flow from chamber 160 to chamber 164 through the power enrichment metering jet 175, conduit 180, economizer valve 184 and conduit 182. The regulator C positions the fuel inlet valve 79 to maintain the fuel differential pressure between chambers 160 and 164 equal to the air differential pressure. Since the economizer valve has increased the available fuel metering area, the fuel flow will increase, thus increasing the mixture richness.

If the airplane is now taken to a higher altitude the mixture-to-scoop air differential pressure for a given weight of air will increase. If this increased differential were transmitted to the chambers 119 and 120 of the regulator the fuel flow would increase and the mixture would become richer with increase in altitude. At ground level the bellows controlled valve 47 has no appreciable restricting effect at the port 48 and air may freely flow from the inlet 10, through tubes 19 into annular chamber 18, through passages 21, 22, 23 and 24 into the regulator chamber 120. The restricted bleed 141 creates a small flow of air from chamber 120, to chamber 119, through

passages 39, 37 and 36, and discharges into the venturi 29. At ground level, chamber 119 freely communicates with the venturi 29 and chamber 120 freely communicates with the air inlet 10. 5 The small bleed 141 creates but a negligible effect in disturbing the pressures in chambers 119 and 120. However, as altitude is attained the bellows 45 expands and valve 47 begins to restrict port 48. The bleed 141 then becomes effective to reduce the pressure in chamber 120. The valve 47 is designed to restrict port 48 such that the differential pressure across diaphragm 93 will remain constant for a given weight of air flow regardless of the altitude or the temperature of the entering air, thus maintaining a substantially constant mixture richness with change in altitude.

If the mixture control valve is in the automatic-rich position of Figure 6 with the engine operating at but moderate power, the economizer valve 183 will be closed and the engine will receive fuel through the automatic-lean metering jet 161 and also through the power enrichment jet 175, automatic-rich metering jet 178 and conduit 177. 20 The regulator C again maintains the unmetered-to-metered fuel pressure differential equal to the air differential but the mixture is enriched because of the increased available fuel metering area. Under these conditions the metering jet 175 has very little effect since it is larger than jet 178, the metering thus being accomplished primarily by the jet 175. However, at high power output with the economizer valve 183 open, the jet 175 becomes the primary restriction and the 25 mixture is enriched but very slightly more than at high power output with the mixture control valve in the automatic lean position. Thus the richness of the mixture at high power output is substantially independent of whether the mixture control valve is in the automatic-rich or automatic-lean position, thus insuring that the engine will receive the desired amount of fuel for maximum power and engine safety.

In an emergency at altitude the pilot may obtain additional richness by moving the mixture control valve 165 to the full-rich emergency position of Figure 7. As previously explained, this opens the valve 26 by-passing the altitude control valve 47 and permits the full venturi-to-scoop differential pressure to be transmitted to the regulator, thus increasing the fuel differential pressure and increasing the mixture richness.

From the foregoing discussion it will be apparent that the regulator C merely regulates the drop in pressure across the metering jets and maintains it equal to the venturi-to-scoop differential pressure; whereas the fuel control unit D controls the available fuel metering area across which the differential pressure is being maintained by the 50 regulator and therefore controls the mixture richness.

As previously pointed out, both the assembled regulator C and fuel control unit D may be separately tested following assembly. The fuel control unit D is then preferably bolted to the regulator C and the combined assembly tested before installing it on the body section A. Suction from any convenient vacuum source, such as a small vacuum pump, may be applied to chamber 119 so as to create any desired differential pressure between chambers 119 and 120, the actual differential pressure applied being measurable with a conventional manometer. Fuel is supplied to the regulator at the desired pressure and a pressure responsive fuel discharge nozzle, forming a part

of the test fixture, is connected to the control unit outlet passage 151. The regulator and control unit thus function just as though installed on an engine and operating at a condition at which the air flow created the applied air differential pressure. A fuel flow meter installed in the fuel line indicates the quantity of fuel passing through the regulator and calibration curves of master venturis indicate the air flow corresponding to the applied air differential. Thus the fuel flow and air flow at this fictitious condition of operation may be determined. The fuel metering characteristic of the combined regulator and fuel control unit may thus be checked before installing it on the body unit A.

During operation, vapor may tend to form in the chambers 117 and 118 of the regulator. As vapor forms, however, it escapes through the small bleed 130 and passage 137 which respectively enter the chambers 117 and 118 adjacent their uppermost portions. Vapor is thus prevented from collecting in the chambers 117 and 118 to an extent which would interfere with operation of the device.

When the engine is to be stopped the mixture control valve 165 is moved to the idle cut-off position and the ignition turned off. It should particularly be noted that in the idle cut-off position the valve 165 and valve 172 cut off all communication between chambers 118 and 117. Fuel will continue to enter chamber 117 until the pressure therein increases to a value slightly above that maintained in the metered chamber by the pressure responsive discharge nozzle, at which time the control rod 90 will move to the left overcoming the idle spring and close the valve 79, thereby preventing any additional fuel from entering chamber 117. If the bleed passage 130 or the fill passage 134 were not closed by the valves 165 and 172, the pressure in chambers 117 and 118 would equalize and permit the light idle spring to keep valve 79 in open position regardless of how high a pressure was attained in these chambers. Therefore, if the cut-off valve were placed for example in the pipe 152, the pressure in chambers 117 and 118 would increase to the supply line pressure and tend to cause fuel leakage past the diaphragms.

If the idle cut-off were not provided, fuel would continue to flow to the engine at the idle rate until the fuel pressure from the fuel pump dropped below the pressure required to open the valve of the discharge nozzle 204. If the engine is hot at the time the ignition is turned off, the engine might continue to run, due to pre-ignition, if the fuel supply is continued. Furthermore, engine heat after shut down may form vapor in the fuel line leading from the pump which would maintain the fuel supply pressure and cause considerable fuel to leak into the engine manifold and interfere with the next starting operation. These difficulties are overcome by the arrangement of Figure 3.

During periods of inoperation, fuel might slowly leak past diaphragms 92 and 94 and gradually collect in chambers 120 and 119 where it would interfere particularly with starting if no means were provided to eliminate it. Also, water or rain entering tubes 19 might tend to collect in chamber 120. In order to eliminate any liquids collecting in chambers 119 and 120, the passage 39 enters chamber 119 at its lowermost portion and is provided with a small bleed 38 entering the induction passage posterior to the throttle. The bleed passage 141 also enters the bottom of chambers 119

and 120. If any water or liquid fuel is present in these chambers the vacuum posterior to the throttle during cranking will draw it out through bleed 38. The passage 140 leading from the passage 37 into the top of chamber 119 is provided to insure that venturi suction will be transmitted to chamber 119 during starting, even though liquid is present therein which would interfere with the passage 39 transmitting to the chamber

119 the moderate starting suctions of but an inch or two of fuel head. During operation a continuous current of ventilating air passes into tubes 19, through passages 21, 22, 23 and 24, into chamber 120, through bleed passage 141, into chamber 119, through passages 39 and 140, into passage 37, and discharges into the induction passage either through bleed 38 or through passage 36 and annulus 35. Liquids are thus continuously drawn out of chambers 119 and 120 as they collect.

Although the invention has been described in connection with one particular charge forming device it will be apparent that it is applicable to charge forming devices of other types. It will also be apparent that the device disclosed is capable of many modifications and it is not intended that the scope of the invention be limited to the form shown and described, nor otherwise than by the terms of the appended claims.

30 I claim:

1. A charge forming device for an internal combustion engine comprising a body unit forming an induction passage having an inlet, a venturi, a throttle posterior to the venturi, and a fuel discharge nozzle posterior to said throttle; a fuel regulator unit separably secured to said body section for regulating the quantity of fuel supplied to the nozzle in accordance with variations in the air flow through the induction passage, said regulator including an unmetered fuel chamber, a metered fuel chamber, a depression chamber, an air chamber, a fuel inlet to the unmetered fuel chamber, a valve in said fuel inlet, means responsive to the pressures in said chambers operably connected to said valve, and yielding means urging said valve toward open position; and a fuel control unit separably secured to one of said units for determining the differential in the pressures in the metered and unmetered fuel chambers for a given rate of fuel flow to the nozzle, said control unit including a fuel conduit having a metering orifice therein: said charge forming device including an air passage leading from the venturi and having a pair of branches respectively entering the depression chamber adjacent the top and bottom thereof, said bottom branch having a restricted connection to the induction passage posterior to the throttle, fuel passages leading from adjacent the bottoms and from adjacent the tops of the metered and unmetered fuel chambers to the fuel conduit, valve means operable to cut off all communication between the metered and unmetered fuel chambers when the engine is to be stopped, and a fuel duct conducting fuel from posterior the metering orifice to said fuel discharge nozzle.

2. A charge forming device comprising a body section forming an induction passage and including an air differential pressure creating means, a fuel nozzle discharging into said passage, a pressure responsive outlet valve in said nozzle, a fuel regulator unit separably secured to the body section and having means for regulating the flow of fuel supplied to said nozzle to establish a fuel metering differential pressure variable in response

to variations in the air differential pressure, a fuel control unit separably mounted and connected to said regulator unit and including variable area fuel metering means for varying the quantity of fuel supplied to the nozzle at a given air and fuel differential pressure to thereby vary the richness of the mixture, and means for supplying fuel at superatmospheric pressure to said regulator unit and said control unit.

3. A charge forming device comprising a body section forming an induction passage, a main fuel discharge nozzle discharging into said induction passage, a fuel regulator unit separably secured to the body section and having means for regulating the flow of fuel to said nozzle to produce a fuel metering differential pressure variable in accordance with variations in the rate of air flow through the passage, a fuel control unit separably secured to the regulator unit and having variable area metering means for varying the relationship of the fuel metering differential pressure to the quantity of fuel supplied to the nozzle for varying the mixture richness.

4. A charge forming device comprising the following separable parts: a body section forming an air passage having an inlet and an outlet and including an air differential pressure creating means; a fuel regulator unit secured to the body section and including a fuel control valve and pressure responsive means for controlling the valve to produce a predetermined fuel metering differential pressure variable in accordance with variations in the air differential pressure; a fuel control unit secured to said regulator unit and including a fuel conduit, flow restricting fuel metering means in said conduit, and fuel passages connecting said conduit anterior and posterior to said restricting means to said pressure responsive means; and an adapter section having an air passage with an inlet adapted to be connected to the body section, and a fuel nozzle receiving fuel from said conduit posterior to said restricting means and discharging into said last named air passage.

5. A charge forming device comprising the following separable parts: a body section forming an air passage having an inlet and an outlet and including a venturi; an adapter section including an air passage having an inlet connected to said body section outlet and a main fuel nozzle discharging into said adapter section air passage; a fuel regulator section secured to said body section and including a fuel control valve, pressure responsive means for controlling said valve, and air passages communicating said pressure responsive means with said venturi and said body section air inlet; and a fuel control unit secured to at least one of said sections and comprising a fuel conduit, area restricting means in said conduit, mechanism for varying the effective area of said area restricting means, fuel passages communicating said conduit anterior and posterior to said area restricting means with said pressure responsive means, and a duct conducting the fuel passing through said area restricting means to said discharge nozzle.

6. A charge forming device comprising the following separable parts: a body section forming an air passage having an inlet and an outlet and including a venturi; an adapter section having an air passage with an inlet secured to said body section outlet and including a fuel discharge nozzle; a fuel regulator section secured to one of said sections and including a fuel control valve

and pressure responsive means for controlling said valve; and a fuel control section secured to at least one of said previously named sections and comprising a fuel conduit, area restricting means in said conduit, and mechanism for varying the effective area of said area restricting means; said sections including passages forming at least portions of the ducts communicating said pressure responsive means respectively with the venturi, and the conduit anterior and posterior to said area restricting means and of a duct conducting fuel from posterior to said area restricting means to said discharge nozzle.

7. A charge forming device comprising the following separable parts: a body unit forming an air passage having an inlet and an outlet; an adapter unit secured to said body unit and having an air passage with a fuel discharge nozzle therein; a fuel regulator unit secured to one of said units and receiving fuel from a source, said regulator unit including a fuel control valve and a pressure responsive means for controlling said valve; a fuel control unit secured to at least one of said units and including a fuel passage and means for varying the effective area of said fuel passage; and an automatic mixture control unit secured to one of said units and including a valve and means responsive to variations in barometric pressure for controlling said valve; and conduits connecting said pressure responsive means with the fuel passage and with the body unit air passage, one of said conduits being controlled by the automatic mixture control unit valve, and a fuel duct conveying fuel from said fuel passage to said discharge nozzle.

8. A charge forming device comprising an induction passage, a fuel conduit discharging into said induction passage, a venturi and a throttle in said induction passage, means for regulating the flow of fuel through said conduit comprising a pressure chamber and a depression chamber, a branched air passage connecting the venturi throat with the upper and lower portions of the depression chamber, a second air passage connecting a point of low suction in the induction passage with the pressure chamber, means responsive to barometric pressure for varying the relative capacities of said air passages, a restricted connection between said chambers, and a drain passage connecting one of said chambers adjacent the lower portion thereof and the induction passage posterior to the throttle.

9. A charge forming device comprising an induction passage, fuel discharging means for discharging fuel into the air flowing through the passage, a fuel conduit supplying fuel to said discharging means, fuel metering means in said conduit for creating a differential in fuel pressures, a pair of air chambers connected to spaced points in the induction passage, a pair of fuel chambers connected to spaced points in the fuel conduit to be subjected to said fuel pressures, means including movable pressure responsive walls in said air and fuel chambers for controlling the flow of fuel to the discharging means, a drain passage connecting the lower portion of one of the air chambers with the induction passage, a restricted passage interconnecting the air chambers at their lower portions, a connection between the lower portions of said fuel chambers, and valve means for closing said connection.

10. The invention defined in claim 9 wherein the charge forming device includes a body portion forming the induction passage, a detachable

regulator unit including said air and fuel chambers and adapted to regulate the fuel flow to control the differential of the pressures in the fuel chambers in accordance with the differential of the pressures in the air chambers, a detachable control unit including the fuel metering means and the said valve means, and a detachable altitude control unit having means responsive to variations in barometric pressure for modifying the relative pressures in the said air chambers.

11. A charger forming device for an internal combustion engine comprising a body unit for creating an air differential pressure variable in response to variations in air flow to the engine comprising an air passage, a venturi, and a throttle posterior to the venturi; a fuel regulator unit separably secured to said body section for varying the fuel flow to the engine to create a fuel metering differential pressure variable in accordance with variations in the air differential pressure comprising a pair of air chambers adapted to be connected to the venturi and air passage anterior to the throttle respectively, a pair of fuel chambers subjected to the fuel metering differential pressure, valve means for controlling the flow of fuel to the engine, and diaphragms subjected to the pressures in said air and fuel chambers for actuating said valve means; and a fuel control unit separably secured to the regulator unit for varying the quantity of fuel supplied to the engine at a given fuel metering differential pressure comprising a fuel conduit transmitting fuel supplied to the engine, area restricting means in the conduit for creating the said fuel metering differential pressure, manual means for varying the effective area of the area restricting means, and means for automatically varying the effective area of the area restricting means.

12. The invention defined in claim 11 comprising in addition an automatic mixture control unit separably secured to the body unit for varying the richness of the mixture in response to variations in pressure resulting from change in altitude comprising a sealed capsule, and a valve controlled by said capsule and operative to modify the pressures in the air chambers.

13. A charge forming device for an internal combustion engine comprising a body unit forming an induction passage having an inlet, a venturi, a throttle posterior to the venturi and fuel discharging means posterior to the throttle; a fuel regulator unit separably secured to said body section for controlling the fuel metering differential pressure including a fuel valve for regulating the flow of fuel, and pressure responsive diaphragms connected to said valve and adapted to form movable walls of an unmetered fuel chamber, a metered fuel chamber, an air chamber and a depression chamber; and a fuel control unit separably secured to one of said units for varying the quantity of fuel supplied to the engine at a given fuel metering differential pressure including a fuel conduit, area restricting means in said conduit for creating the fuel metering differential pressure, and means for varying the effective area of said area restricting means: said charge forming device including an air passage leading from the venturi and having a pair of branches respectively entering the upper and lowermost portions of the depression chamber, the latter having a restricted connection to the induction passage posterior to the throttle, and fuel passages leading from adjacent the bottoms

and adjacent the tops of the metered and unmetered fuel chambers to the fuel conduit.

14. In liquid fuel control apparatus for an internal combustion engine, a fuel conduit for supplying fuel to the engine and including fuel metering means, a pair of fuel chambers communicating with the fuel conduit anterior and posterior to the fuel metering means, each of said chambers having a movable wall, means controlled by movement of said walls for regulating the flow of fuel through the conduit, a connection between the lower portions of said chambers to permit simultaneous filling of the chambers, an element operable from a point remote from the apparatus, and means actuated by said element for varying the effective area of said fuel metering means and for opening and closing said connection.

15. In liquid fuel control apparatus for an internal combustion engine, a fuel conduit for transmitting fuel to the engine, means in the conduit for creating a differential in the pressures at spaced points in the conduit, two fuel chambers respectively in communication with the conduit at said spaced points, each of said chambers including a movable wall, a valve in the conduit controlled by movement of said walls for regulating the flow of fuel through the conduit, a connection between the lower portions of the chambers, a vent passage from the upper portion of at least one of said chambers to the fuel conduit posterior to the valve and anterior to at least one of said spaced points, and means operable from a point remote from the device for opening and closing said connection and said vent passage.

16. In liquid fuel control apparatus for an internal combustion engine, a fuel conduit for transmitting fuel to the engine, a pair of fuel chambers freely communicating with said conduit at spaced points, each of said chambers having a movable pressure responsive wall, valve means controlled by movement of said walls for regulating the flow of fuel through said conduit, yielding means urging said valve means in a direction to increase the fuel flow, fuel metering means in the conduit for creating a differential between the pressures at said spaced points, means including said conduit and additional passages for intercommunicating the upper portions of the chambers and the lower portions of the chambers respectively to thereby permit simultaneous filling of the chambers, and valve means operable from a point remote from the engine for closing said intercommunicating means to thereby cut off all communication between said chambers.

17. In a fuel control system for an internal combustion engine having an air supply duct, a venturi in the duct, a throttle in the duct posterior to the venturi, a fuel conduit for supplying fuel to the engine, an air chamber, a depression chamber, an unmetered fuel chamber, a metered fuel chamber, each of said chambers including a movable wall, means operably connected to said movable walls for controlling the flow of fuel through the conduit, an air passage leading from the venturi and having a pair of branches respectively entering the depression chamber adjacent the top and bottom thereof, an air passage leading from the air supply duct anterior to the throttle to the air chamber, an air passage interconnecting said air and depression chambers, means responsive to variations in barometric pressure for controlling the relative ca-

pacities of said air passages, a restricted connection between the air supply duct posterior to the throttle and the lower portion of one of said air chambers, means intercommunicating the upper portions of the unmetered and metered fuel chambers, the lower portions of the unmetered and metered fuel chambers, and communicating the unmetered and metered fuel chambers with the fuel conduit, and means operable to cut off all communication between the unmetered and metered fuel chambers when the engine is to be stopped.

18. A fuel feeding system for an internal combustion engine comprising an air passage for supplying air to the engine, a throttle in said passage, a venturi in the passage anterior to the throttle, a fuel conduit for supplying fuel to the engine, means for regulating the flow of fuel through said conduit comprising a pressure chamber and a depression chamber, passages connecting the venturi adjacent its throat with the upper and lower portions of the depression chamber, another air passage connecting the pressure chamber to the induction passage anterior to the throttle at a point of low suction, a restricted connection between said pressure and depression chambers, and a drain passage connecting one of said chambers adjacent the lower portion thereof and the induction passage posterior to the throttle.

19. A charge forming device for an internal combustion engine comprising the following separable parts: a body unit forming an air passage having an inlet and an outlet and including a differential pressure creating means; a fuel regulator unit separably mounted and receiving fuel from a source, said regulator unit including a fuel control valve and pressure responsive means for controlling said valve; a fuel control unit sep-

5 arably mounted and including a fuel passage and means for varying the effective area of said fuel passage; and an automatic mixture control unit secured to one of said units and including a valve and means responsive to variations in barometric pressure for controlling said valve; and conduits connecting said pressure responsive means respectively with the fuel passage, the air passage, and the differential pressure creating means, one of said conduits being controlled by the automatic mixture control unit valve, and means including a fuel duct for conveying fuel from said fuel passage to the engine.

15 20. A charge forming device for an internal combustion engine comprising a body unit forming an induction passage and including an air differential pressure creating means and a throttle posterior thereto; a fuel regulator unit separably secured to the body section and having means for regulating the flow of fuel to the engine to produce a fuel metering differential pressure variable in accordance with variations in the air differential pressure; a fuel control unit separably secured to the regulator unit and having variable area metering means for varying the relationship of the fuel metering differential pressure to the quantity of fuel supplied the engine for varying the mixture richness; and an automatic mixture control unit separably secured to one of the units for varying the richness of the mixture in response to variations in pressure resulting from change in altitude comprising a calibrated passage, a valve cooperating with said passage for varying the effective area thereof to modify the quantity of fuel supplied to the engine, and a sealed capsule for operating said valve.

FRANK C. MOCK.
